[57] **CLAIM**

The ornamental design for a back pressure regulator, substantially as shown and described.

DESCRIPTION

FIG. 1 is a right side elevational view of a back pressure regulator showing my new design, the left side being a mirror image of the right side shown;
FIG. 2 is a rear elevational view thereof;
FIG. 3 is a front elevational view thereof;
FIG. 4 is a top plan view thereof; and
FIG. 5 is a bottom plan view thereof.
